TESTING MACHINE FOR WASHING MACHINE
WRINGERS AND THE LIKE

Alfred R. Oberwegner, Los Angeles, Calif.

Application August 21, 1946, Serial No. 691,898

9 Claims. (Cl. 74—16)

1

My invention relates to a machine or apparatus for testing washing machine wringer assemblies, and the like.

In conventional washing machines the wringer assemblies may be readily removed and may be separately tested for proper construction and operativeness. These wringer assemblies commonly consist of a wringer head, which is the drive mechanism, and the wringer unit, or the wringer rolls.

One of the principal objects of this invention is to provide a machine or apparatus of this class whereby a washing machine wringer assembly, and particularly the wringer head thereof, or like article, may be readily placed and readily or simultaneously connected with a drive means, whereby the wringer head, or other article, may be easily and quickly tested for proper operation, an important feature being the provision of a machine or apparatus whereby innumerable wringer heads of the same type, or like articles, may be readily placed thereon and tested without further adjustments.

An important object of this invention is the provision of a machine or apparatus of this class, which may be easily and quickly adjusted to various types and shapes of wringer heads, or other articles, for testing or otherwise operating the same.

Another important object of this invention is the provision of a novel feature in connection with the drive means for easily and quickly adjusting the same for accommodating various types and sizes of the drive means of wringer heads, or other articles.

A further important object of this invention is the provision of a novelly constructed and simple table for supporting washing machine wringer assemblies, and particularly wringer heads, or the like, for accommodating the same to other portions of the machine.

With these and other objects in view, as will appear hereinafter, I have devised a machine or apparatus for testing washing machine wringer assemblies, or the heads thereof, or the like, and a machine or apparatus of this class having certain novel features of construction, combination, and arrangement of parts and portions, as will be hereinafter described in detail and particularly set forth in the appended claims, reference being had to the accompanying drawings and to the characters of reference thereon, which form a part of this application, in which:

Fig. 1 is a side view of one form of my machine for testing washing machine wringer heads,

2

showing a washing machine wringer assembly supported thereon in a position to be tested, portions being broken away and in section to facilitate the illustration:

5 Fig. 2 is a plan view thereof;
Fig. 3 is a sectional view thereof in plan, taken through 3—3 of Fig. 1; and
Fig. 4 is an enlarged sectional view thereof, taken through 4—4 of Fig. 1.

10 My machine or apparatus, shown in the drawings, is supported on a frame consisting of a horizontal plate member 1 and legs extending downwardly therefrom, these legs comprising a single forward leg 2 and two rear legs 3. The plate member 1 has downwardly extending inwardly threaded bosses 1^a and 1^b into which the upper ends of the legs 2 and 3 are screwed.

A table T is provided at the upper end of the machine, and extends forwardly from the 20 rear side of the machine, for supporting the wringer assembly, designated W, to be tested. This table has a horizontal frame 4 provided at the lateral sides of its rear end with downwardly extending bosses 4^a into which are secured, by screws 5, the upper ends of rods 6. These rods extend downwardly into tubes 7, which are screwably secured at their lower ends into the upper ends of the bosses 1^b.

The legs 3 are hollow, and within these legs, 30 and within the lower ends of the tubes 7, are compression springs 8 for resiliently supporting the lower ends of the rods 6. The lower ends of the legs 3 have plugs 9 for retaining the springs 8. The springs 8 facilitate the raising of the rods 6, but they are positively secured in vertically adjusted positions by thumb screws 10.

The table T has a flanged supporting platform for the wringer assembly, this platform comprising flanged cleats 11, at its opposite lateral sides. These cleats consist of base portions 11^a, forming the supporting platform for the wringer assembly, and lateral or outer upwardly extending flanges 11^b for locating the wringer assembly laterally. The base portions of the cleats rest upon the frame 4 and are adjustably secured thereto by bolts 12. These bolts extend downwardly between lateral members 4^b of the frame 4, and are held against the under sides of the members 4^b by straps 13, these straps being held against the under sides of the members 4^b by wing nuts 12^a. Such mounting and securing of the flanged cleats 11 permits the same to be readily adjusted for locating a wringer assembly 45 W of any shape. These flanged cleats may as- 50

sume angular positions, as shown by dotted lines in Fig. 2.

At the forward end of the machine is a vertical drive shaft 21, which is operated by a motor 22 resting upon the supporting plate 1 behind the drive shaft and below the table T. The drive shaft extends upwardly from a gear box 23, which is supported at the forward end of the supporting plate 1 by studs 24. These studs are adjustable vertically with respect to the supporting plate 1 and are locked in position by nuts 25. In the gear box is mounted a worm gear 26, through the axis of which the shaft 21 extends, and this worm gear is driven by a worm 27, which is directly connected by a flexible coupling 28 to the shaft of the motor 22.

The shaft 21 is adjustable axially within the hub of the worm gear 26, and is splined or keyed thereto, so that the shaft is rotated in various adjusted vertical positions thereof. The shaft is normally held in a raised position by a spring 30 surrounding the shaft, thus holding the shaft resiliently in raised position. However, the shaft is locked in a determined vertical position by a collar 31 and a set screw 32. The collar 31 is forced against the upper side of the gear box 23 by the spring 30 and secured to the shaft 21 by the set screw 32, which extends into the keyway of the shaft 21, when the latter is forced downwardly by the drive shaft of the wringer assembly W.

To prevent the shaft 21 from being forced by the spring 30 from or above the worm gear 26, the shaft 21 extends to below a horizontal strap 33 at the bottom side of the gear box. A pin 34 is provided at the lower end of the shaft 21 for engaging the under side of the strap 33 to prevent the spring from forcing the shaft upwardly beyond its predetermined limit.

At the upper end of the drive shaft 21 is a clutch member 35, which is arranged normally removably to hold the shank of an adapter 36 which extends upwardly in alignment with the shaft. The lower end of the adapter has a pin or key 37 for non-rotatably holding the adapter with respect to the shaft.

A plurality of adapters may be provided for the machine, to accommodate different wringer heads.

The upper ends of these adapters 36 may have variously shaped recesses, keys, or drive portions 36^a for receiving or connecting the upper end of the drive shaft with the lower end 38^a of the drive means 38 with which one end of the wringer assembly W is normally provided.

Thus, a wringer assembly may be placed upon the table T with the drive means 38^a inserted into the socket, or other means, of the adapter 36 in order to rotate or otherwise operate or test the wringer head by means of the motor 22.

The table T is raised to accommodate certain types of wringer heads, or the like, and the same are locked in the desired vertical position by the thumb screws 10. The drive shaft 21 is then adjusted to assume a fixed vertical position by means of the lock bolt 32.

Though I have shown and described a particular construction, combination, and arrangement of parts and portions of my machine as adapted to test or operate a washing machine wringer assembly, I do not wish to be limited to the same, but desire to include in the scope of my invention the construction, combination, and arrangement substantially as set forth in the appended claims.

I claim:

1. In a testing machine of the class described, a frame, a drive shaft rotatable thereon, a motor on the frame, means for operatively connecting the motor to the drive shaft, and a support mounted on the frame and spaced laterally with respect to the axis of the drive shaft and adjustable on the frame in a direction parallel to the axis of the shaft, for supporting the article to be tested, said article having a downwardly extending drive means adapted, when the article is supported on the support, to be aligned with the drive shaft, the latter having means for readily detachably connecting the shaft to the drive means of said article.
2. In a testing machine of the class described, a frame, a drive shaft rotatable and axially shiftable thereon, a motor on the frame, means for operatively connecting the motor to the drive shaft, and a support mounted on the frame and spaced laterally with respect to the axis of the drive shaft and adjustable on the frame in a direction parallel to the axis of the shaft, for supporting the article to be tested, said article having a downwardly extending drive means adapted, when the article is supported on the support, to be aligned with the drive shaft, the latter having means for readily detachably connecting the shaft to the drive means of said article.
3. In a testing machine of the class described, a frame, a drive shaft rotatable thereon, and resiliently shiftable in an axial direction, a motor on the frame, means for operatively connecting the motor to the drive shaft, and a support mounted on the frame and spaced laterally with respect to the axis of the drive shaft and adjustable on the frame in a direction parallel to the axis of the shaft, for supporting the article to be tested, said article having a downwardly extending drive means adapted, when the article is supported on the support, to be aligned with the drive shaft, the latter having means for readily detachably connecting the shaft to the drive means of said article.
4. In a machine of the class described, a frame, a vertical drive shaft rotatable thereon, a motor on the frame, means for operatively connecting the motor to the drive shaft, and a vertically adjustable table mounted on the frame above the motor for supporting a wringer to be tested, said wringer having a drive means at one end, the drive means being adapted to be positioned beyond the table and to be aligned with the drive shaft located therebelow, the drive shaft having means for readily detachably connecting the shaft to the drive means of the wringer.
5. In a machine of the class described, a frame, a vertical drive shaft rotatable and axially shiftable thereon, a motor on the frame, means for operatively connecting the motor to the drive shaft, and a vertically adjustable table mounted on the frame above the motor for supporting a wringer to be tested, said wringer having a drive means at one end, the drive means being adapted to be positioned beyond the table and to be aligned with the drive shaft located therebelow, the drive shaft having means for readily detachably connecting the shaft to the drive means of the wringer.
6. In a machine of the class described, a frame, a vertical drive shaft rotatable thereon and resiliently shiftable in an axial direction, a motor on the frame for operating the drive shaft, and a vertically adjustable table mounted on the frame above the motor for supporting a wringer.

to be tested, said wringer having a drive means at one end, the drive means being adapted to be positioned beyond the table and to be aligned with the drive shaft located therebelow, the drive shaft having means for readily detachably connecting the shaft to the drive means of the wringer.

7. In a machine of the class described, a frame, a vertical drive shaft rotatable thereon, a motor on the frame, means for operatively connecting the motor to the drive shaft, and a table mounted on the frame above the motor for supporting a wringer to be tested, said wringer having a drive means at one end, the drive means being adapted to be positioned beyond the table and to be aligned with the drive shaft located therebelow, the drive shaft having means for readily detachably connecting the shaft to the drive means of the wringer, said table having a cleated platform comprising flanged cleats at the opposite sides of its upper face, said cleats having base portions and upwardly extending flanges at their outer portions, said cleats being adjustable laterally and angularly with respect to each other for locating the drive means of the wringer with respect to the drive shaft.

8. In a testing machine of the class described: a frame; a drive shaft rotatable and axially shiftable on the frame; a motor on said frame; a power transmission means operatively connected to the motor and said shaft for rotating the latter, said transmission means including a gear box; a support for supporting the article to be tested, said article having a driven shaft adapted, when the article is in place on the support, to align with said drive shaft; cleat means on said support engageable with the article for retaining the same in selected positions on the support; connecting means on said drive shaft by which the latter can be readily detachably disconnected to said driven shaft; and a stop element on said drive shaft engageable against said gear box for limiting axial shifting movement of said drive shaft toward said support.

9. In a testing machine of the class described: a frame; a drive shaft rotatable and axially shiftable on the frame; a motor on said frame; a power transmission means operatively connected to the motor and said shaft for rotating the latter, said transmission means including a gear box; a support for supporting the article to be tested, said article having a driven shaft adapted, when the article is in place on the support, to align with said drive shaft; cleat means on said support engageable with the article for retaining the same in selected positions on the support; connecting means on said drive shaft by which the latter can be readily detachably connected to said driven shaft; a spring surrounding said drive shaft between said gear box and said connecting means for normally urging said drive shaft toward said support; and a stop element on said drive shaft engageable against said gear box for limiting axial shifting movement of said drive shaft toward said support.
